UNITED STATES PATENT OFFICE.

ERNST TYRMAN, OF CHICAGO, ILLINOIS, ASSIGNOR TO TYRMAN ELECTRIC CORPORATION, A CORPORATION OF ILLINOIS.

CONDENSER MOUNTING AND ADJUSTING MECHANISM.

Application filed March 28, 1927. Serial No. 178,907.

This invention relates to improvements in condenser mountings and adjusting mechanism and is more especially adapted for use in connection with radio apparatus, for example, radio receiving sets. The invention relates more particularly to a condenser adjusting mechanism of the drum type with a vernier dial.

One of the features of my invention is to provide a condenser mounting that has practically universal use, in that it is adapted to carry and support practically any type of condenser used in connection with radio receiving sets. The apparatus is so constructed that the condenser mounting not only carries and supports the condenser but also carries the adjusting mechanism therefor, comprising a graduated drum and a vernier dial in connection therewith. The apparatus is so arranged that when the mounting is attached to the back of a radio panel having an opening therethrough, a portion of the periphery of the drum and a portion of the periphery of the vernier dial will project slightly through said opening, said portions being adjacent, to permit adjustment of the condenser.

My improved apparatus may be very cheaply and easily made, is simple and neat in appearance, strong, and durable. The adjusting mechanism is also accurate and reliable, and permits fine and close adjustment of the condenser.

In that form of device embodying the features of my invention shown in the accompanying drawings, Fig. 1 is a view in front elevation of a radio panel showing the appearance of portions of the graduation drum and vernier dial of my improved apparatus as they appear when the same is mounted on a panel, Fig. 2 is a similar view showing the panel removed, Fig. 3 is a view taken as indicated by the line 3 of Fig. 2, Fig. 4 is an isometric view of the mounting plate or bracket forming a part of my improved apparatus, Fig. 5 is a view taken as indicated by the line 5 of Fig. 3, Fig. 6 is a fragmentary view similar to Fig. 3 showing a modified form, Fig. 7 is a view similar to Fig. 3 showing another modified form, Fig. 8 is a view taken as indicated by the line 8 of Fig. 7, and Fig. 9 is a view taken as indicated by the line 9 of Fig. 8.

As shown in the drawings, 4 indicates a bracket or mounting plate preferably formed

out of a piece of sheet metal substantially rectangular in shape and provided at one edge with two ears or lugs 7, 7 for fastening the same to a radio panel, and at the opposite edge with a similar ear or lug 6 adapted to have attached thereto one end of a spiral spring 5 for a purpose to be hereinafter stated. The plate 4 is preferably provided with a plurality of different sized and shaped openings indicated in general by 20, 20 for the purpose of permitting condensers of various types to be secured thereto. In general, it is intended that the plate 4 shall have a sufficient number of such openings of different shapes and sizes so that practically any condenser now on the market can be readily attached to the plate. Obviously, however, the user can easily drill or punch additional holes or openings as desired to permit attachment to the plate of any type of condenser.

12 indicates the radio panel itself provided with an opening 13. Preferably a suitable ornamental framing plate 14 surrounds the opening in the panel, but such a plate forms no part of the present invention. The plate 4 is attached to the radio panel on the reverse side by means of suitable bolts or screws passing through the ears 7, 7, to support the plate 4 substantially at right angles to the panel.

As stated before, the condenser is mounted on the plate 4 by means of screws or bolts passing through suitably located openings 20 so that the shaft of the condenser will extend through the central opening 21 in the plate. I have here indicated in general a condenser by 11 (see Fig. 2) and it will be seen that it is fastened to the plate 4 by the two screws 22, 22 passing through two of the holes 20, 20. When thus located, the shaft 23 projects through the opening 21.

1 indicates a graduation drum made of any suitable material, for example bakelite, hard rubber, metal, or the like, and provided with the usual graduations 1^a as shown. The graduation drum 1 is provided with a hollow shaft 9 adapted to receive the condenser shaft 23 and a set screw 10 is provided to attach the graduation drum shaft to the condenser shaft.

2 indicates a vernier wheel or dial having its axis parallel with the axis of the graduation drum. Portions of the peripheries of the drum and dial lie adjacent each other; 110

and when the apparatus is mounted on a panel, said portions of the peripheries project through the opening 13 in the panel where they are accessible to an operator.

5 The vernier dial 2 is mounted on a shaft 24 carried by the swinging end of an arm 25 having one end pivoted at 26 on a post or bolt 27 mounted on the plate 4. The vernier dial 2 is mounted on the shaft 24 in the 10 following manner. Said dial is preferably attached to a collar 30 on said shaft; and said collar also carries a small gear or pinion 31. The drum shaft 9 also carries a pinion 32. One end of the spring 5, above referred to, is 15 attached to a short projection 25^a on the swinging end of the arm 25. The parts are so arranged that the spring 5 yieldingly draws the periphery of the small pinion 31 against the periphery of the pinion 32 so 20 that there will be friction engagement therebetween. It will be seen, therefore, that rotation of the dial 2 will turn the pinion 31 to turn the pinion 32 and thus move the drum 1. Since the pinion 31 is considerably 25 smaller than the pinion 32, a vernier adjustment is afforded. Obviously, the wheels 31 and 32 need not be pinions or gears as long as frictional engagement between their peripheries is afforded. Any kind of frictional contact may be obtained by any suitable 30 means as, for example, by milling, knurling or roughening said peripheries.

In Fig. 6 I have shown a modified form of device in which the drum 1 instead of having the gear 32 on its shaft, is provided at its periphery with an internal gear 50. In such case the spring 5 is omitted and a spring 5^a is provided attached to the arm 25 and to one of the lips 7 to pull the arm 40 25 the other way to bring the gear 31 in contact with the teeth of the internal gear 50 on the drum. In such an arrangement, rotation of the dial 2 will rotate the drum 1 in the same direction.

45 In a device shown in Fig. 7 I have dispensed with the pivoted arm 25. In a device there shown, 124 indicates the vernier dial shaft which has its outer end supported between two inwardly projecting ears 200, 200 formed out of material constituting a part of the bracket or mounting plate 104. These ears 200, 200 are slightly rounded, as shown in Fig. 9, to form a bearing or sup-

port for the end of the shaft 124. Thus formed, they prevent up and down rocking 55 movement of the shaft, but permit a very slight movement in a horizontal plane so that the friction wheel 131 can be held in engagement with the friction wheel 132 carried by the drum shaft 109. The small 60 wheel 131 is fastened to a collar 130 which also carries the vernier wheel or dial 102. 105 indicates a spring attached to the collar 105 surrounding the collar 130 and the other end of this spring is attached to a 65 post 106 so that the wheels 131 and 132 are held in frictional engagement. Except as herein stated, the other parts of the device shown in Figs. 7, 8, and 9 are similar to those 70 in the other forms.

75 While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly 80 as possible in view of the prior art.

85 What I claim as new, and desire to secure by Letters Patent, is:

Apparatus of the character described comprising; a member adapted to carry a condenser; means for attaching said member to a radio panel with an opening therethrough; a graduation drum shaft; means for attaching the drum shaft to the shaft of a condenser carried by the condenser carrying member; a drum on the drum shaft; two 90 inwardly projecting shaft supporting members carried by the condenser carrying member; a vernier dial shaft supported by said shaft supporting members and having its axis parallel to the axis of the drum shaft; a dial on the dial shaft, portions of the peripheries of the drum and dial lying adjacent each other, said adjacent portions adapted to project through said opening in the panel when the condenser carrying member is mounted thereon; and a connection 95 between the dial and the drum whereby rotation of the former will rotate the latter.

100 In witness whereof, I have hereunto set my hand this 25th day of March, A. D. 1927.

ERNST TYRMAN.
